US00D963585S

(12) **United States Design Patent** (10) **Patent No.:** **US D963,585 S**
Xiong (45) **Date of Patent:** **** Sep. 13, 2022**

(54) **POWER STRIP**

(71) Applicant: **GUANGE (SHENZHEN) ELECTRIC CO., LTD.**, Shenzhen (CN)

(72) Inventor: **Zeji Xiong, Xinyi (CN)**

(73) Assignee: **GUANGE (SHENZHEN) ELECTRIC CO., LTD.**, Shenzhen (CN)

(**) Term: **15 Years**

(21) Appl. No.: **29/777,894**

(22) Filed: **Apr. 8, 2021**

(51) LOC (13) Cl. **13-03**

(52) U.S. Cl.

USPC **D13/139.8**

(58) **Field of Classification Search**

USPC ... D13/123, 133, 137.1, 137.2, 137.3, 137.4, D13/138.1, 138.2, 139.1, 139.2, 139.3, D13/139.4, 139.5, 139.6, 139.7, 139.8, D13/151, 152, 153, 154, 155, 156, 157, D13/158, 159, 184, 199, 103, 107, 108 CPC H01R 13/00; H01R 13/03; H01R 13/04; H01R 13/10; H01R 13/35; H01R 13/44; H01R 13/453; H01R 13/4534; H01R 13/502; H01R 13/514; H01R 13/631; H01R 13/639; H01R 13/6633; H01R 13/6666; H01R 13/6675; H01R 13/7135; H01R 31/02; H01R 31/06; H01R 31/065; H01R 13/11; H01R 13/518; H01R 13/642; H01R 13/652; H01R 25/003; H01R 25/006; H01R 43/26; H01H 71/62; H01H 73/14

CLAIM

The ornamental design for a power strip, as shown and described.

DESCRIPTION

FIG. 1 is a perspective view of a power strip showing my new design;

FIG. 2 is another perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof;

FIG. 8 is a bottom plan view thereof; and,

FIG. 9 is an enlarged view of portion 9 shown in FIG. 1. The dash-dash broken lines in the drawings depict portions of the power strip that form no part of the claimed design. The dot-dash broken lines represent boundaries of the enlarged portions and form no part of the claimed design.

1 Claim, 9 Drawing Sheets
